UNITED STATES PATENT OFFICE.

ARTHUR E. TILLISON, OF BELTON, MONTANA.

WRENCH.

1,110,243.

Specification of Letters Patent.

Patented Sept. 8, 1914.

Application filed July 24, 1908. Serial No. 445,212.

To all whom it may concern:

Be it known that I, ARTHUR E. TILLISON, a citizen of the United States, residing at Belton, in the county of Flathead and State 5 of Montana, have invented new and useful Improvements in Wrenches, of which the following is a specification.

My invention relates to a wrench structure and has for its object to provide a device of this character which is particularly simple in construction, efficient in practice and one which can be manufactured and sold at a comparatively low cost. The other elements shown in connection with the wrench 10 are for illustrative purposes only and form no part of the present invention.

With the above and other objects in view the invention consists in the combination and in the arrangement of parts to be hereinafter more fully described and claimed.

These and other objects may be attained by means of the construction illustrated in the accompanying drawing, in which:—

Figure 1 is a side elevation of my improved tool, Fig. 2 is an edge elevation of the same, Fig. 3 is a transverse sectional view, and Fig. 4 is a transverse sectional view taken through the handle.

Referring to the drawing for a more particular description of the invention, numeral 1 designates the tool and 2 the handle. The handle 2 of the wrench comprises intermediate body members 2^a and side members 2^b, the latter being secured to the former by screws 2^c. Rising vertically from the intermediate body members is a pair of spaced parallel guide rods 3 and 4, upon the upper ends of which is mounted the stationary jaw 5 of the wrench. The movable jaw of the wrench is designated by the numeral 8, and slidably mounted on the guide rods 3 and 4, the rearward movement of the movable jaw being limited by the forward end of the handle 2.

45 A feed screw 6 is interposed between the guide rods 3 and 4, and has its upper end journaled in the stationary jaw, the said feed screw being also extended through the movable jaw and threadedly engaging the same and adapted when operated to effectuate adjustments of the movable jaw.

The intermediate body members of the handle are provided with a lining guide channels 3^a for receiving the lower end of the feed screw 6, the lower terminal of the feed screw extending beyond the lower terminals of the

intermediate guide members 2^a and the side members 2^b and provided with a manipulating member 7. A bearing disk 3^b is fixed to the lower end of the feed screw and is 60 rotatably held in a socket 18 formed in the respective body members 2^a, the said socket being intercepted by the said channels 3^a. The side members 2^b of the handle are recessed at 19 in the inner faces at the point 65 of the socket 18, and into which projects the periphery of the bearing disk located in the socket.

The jaw 5 has formed in the top thereof a V-shaped jaw 9 which constitutes an alligator wrench adapted for use on pipes and the like. Formed adjacent the bottom edge of the jaw 5 are a plurality of teeth 10. The top portion 11, of the jaw 8 and the serrated edge 10, serves also as a pipe 70 wrench. The space 12 between the portion 13 of the jaw 5 and the portion 14 of the jaw 8, serves as a wrench for square nuts and also as a vise. The jaw 8 is so constructed to provide a hatchet 15, a hammer 75 16, and a nail extractor 17 formed integral with the head. The jaw 5 constitutes a head and forms a weight and serves to connect the outer ends of the guide rods 3 and 4 and to form a bearing for the outer end 80 of the threaded shank 6. The jaw 8 provides a hatchet which may be used in the ordinary manner of a hatchet blade. By turning the operating member 7 the hatchet blade 8 is moved upon the guide rods 3 and 90 4 toward and from the head 5 and the handle 2, thereby varying the effective leverage and weight.

Having thus described the invention what is claimed as new, is:—

95 A wrench comprising a handle having a pair of fixed parallel guide rods extending therefrom, a fixed jaw secured to the outer ends of said rods, a screw coextensive with said guide rods and interposed between and having its outer end mounted to freely revolve in said fixed jaw, the movable jaw slidably on said guide rods and having a threaded passage receiving said screw, the guide rods serving to hold the sliding jaw 100 against rotation on said screw and to maintain coacting position of said sliding jaw relatively of said fixed jaw, a member revolvably mounted at one end of the handle fixed to the inner end of said screw, the 105 forward end of said handle forming a stop to hold the sliding jaw against movement.

on to said handle, the handle comprising intermediate body members formed on the ends of said rods, and having a passage therethrough for the inner end of said screw, 5 side members detachably connected with said body members and a disk mounted in the handle and fixed on the screw and having portions respectively extending into the

intermediate and side members and free to revolve therein. 10

In testimony whereof I affix my signature in presence of two witnesses.

ARTHUR E. TILLISON.
